UNITED STATES PATENT OFFICE.

WILLIAM F. JACOBS, OF OTTAWA, ILLINOIS, ASSIGNOR TO J. E. PORTER COMPANY, OF OTTAWA, ILLINOIS, A CORPORATION OF ILLINOIS.

CATTLE-STANCHION.

1,080,065.

Specification of Letters Patent.

Patented Dec. 2, 1913.

Original application filed July 12, 1912, Serial No. 708,950. Divided and this application filed January 6, 1913. Serial No. 740,275.

To all whom it may concern:

Be it known that I, WILLIAM F. JACOBS, a citizen of the United States, and a resident of Ottawa, in the county of La Salle 5 and State of Illinois, have invented certain new and useful Improvements in Cattle-Stanchions; and I do hereby declare that the following is a full, clear, and exact description thereof, reference being had to the accompanying drawings, and to the letters of 10 reference marked thereon, which form a part of this specification.

This invention relates to improvements in cattle-stanchions of the type comprising two 15 oppositely facing, vertically arranged, upright side members or bars pivoted or hinged together at their lower ends and latched together at their upper ends, whereby the stanchion may be opened to permit 20 the insertion of the head of an animal, and then be closed to prevent the withdrawal of the same.

The invention has for one of its primary objects, to provide such a construction in 25 stanchions, that when the side bars are unlocked they will immediately and automatically swing or spring apart and thus avoid the necessity of grasping the bars to swing them apart in opening the stanchion.

30 The invention consists in the matters hereinafter described and more particularly pointed out in the appended claims.

In the accompanying drawings illustrating my invention—Figure 1 is a view in front 35 elevation of a stanchion having my invention applied thereto, said stanchion being of the type that is supported in a stall; the supporting and attaching devices for the same being shown; Fig. 2 is a view in side 40 elevation of the same parts shown in Fig. 1, taken in a plane indicated by the broken line 2—2 of said figure; Fig. 3 is a view representing an enlarged horizontal section taken in a plane indicated by the line 3—3 45 of Fig. 1, the full lines showing the attaching devices for the stanchion in one position and the dotted lines in another or adjusted position; Fig. 4 is a view similar to Fig. 2, showing the stanchion in one of the 50 adjusted positions corresponding with that indicated by the dotted lines in Fig. 3; Fig. 5 is a view representing an enlarged vertical section of the lower ends of the side members or bars of the stanchion, showing in

section the hinge for connecting the same, 55 and to which my invention is applied.

Referring to the drawings, illustrating in detail one of the preferred forms of my invention, the same is shown as applied to a stanchion A which is arranged in a vertical 60 or upright position in a stall by being supported from the top and attached to the bottom of the stall. Said stanchion A, as shown, comprises two connected oppositely facing, vertically arranged, upright bars 65 or side members B, C, having their upper and lower ends bent or curved inwardly toward each other. Said bars B, C are connected at their lower ends by a hinge of any preferred construction and are provided at 70 their upper ends with a detachable connection, preferably in the form of a snap latch. As shown in the drawings, the hinged connection for the bars B, C comprises two castings b, c, the former being rigidly secured to the lower end of the bar B, and the latter to the corresponding end of the bar C. Said casting b is provided with an eye b' at its free end, which is adapted to enter between the arms of a 80 yoke c' provided on the similar end of the casting c, the two being connected by a pivot bolt b². The yoke c' of the casting c is provided with an outwardly projecting lug or finger c² forming an extension of the 85 casting and adapted to strike the lower end of the bar B when the bar C is swung about the pivot bolt b². By this construction, the bars B, C are prevented from being swung apart farther than necessary to permit the 90 head of the animal to pass between them.

As shown in the drawings, the snap latch construction, constituting the detachable connection for the upper ends of the bars B, C, of the stanchion, comprises a casting b³ 95 rigidly secured to the upper end of the bar B and provided with a yoke b⁴ projecting beyond the end of the bar B. The forward end of said yoke b⁴ is arched or curved upwardly so that the upper end of the bar C 100 may enter between its arms when swung toward the bar B. The bar C is provided with an upright lug at its upper end, said lug being adapted to enter within a suitable aperture provided therefor in the end of a 105 spring-pressed locking latch b⁵ pivoted to an upright forked member b⁶ secured on the upper end of the bar B. Said locking latch

*b*⁵ is provided with a finger piece *b*⁷ so that the same may be depressed for releasing the bars B, C.

The devices for supporting the stanchion and adapted to permit its adjustment in a horizontal direction toward or from the entrance or open end of the stall, and as shown, are like those shown in my prior application, Serial Number 708,950, filed July 12, 1912, of which this is a division and embrace features as follows: The upper plates D, D are attached to a horizontally arranged, overhead rail F of the stall by split collars G, G clamped on said rail in horizontal, spaced relation to each other, by bolts *g*, *g* passing through lugs or ears on said collars at the split ends thereof. Each upper plate D, D and each lower plate E, E is provided with a longitudinal slot *e*. A bolt *d*', *d*' projects through the slot *e* in each of the upper plates D, D, and a bolt *e*', *e*' projects through the slot *e* in each of the lower plates E, E. The heads of the upper bolts *d*', *d*' are connected with the collars G, G, and the lower ends of said bolts have clamp nuts *d*², *d*² applied thereto. Said lower bolts *e*', *e*' are anchored at their lower ends in the floor of the stall and have clamp nuts *e*², *e*² applied to their upper ends. On each bolt *d*', *d*' is a washer *d*³, while on each lower bolt *e*', *e*' is a similar washer *e*³. The face of each upper plate D, D at the sides of the slot *e* therein, and against which washer *d*³ is adapted to bear, is provided with transverse serrations or ribs *d*⁴ which are adapted to be engaged by complementary ribs on the adjacent face of said washer *d*³. Like ribs are formed on each of the lower plates E, E, and the lower washers *e*³. Said plates D, D and E, E of each set are connected at their adjacent ends by relatively short plates or link members J in the upper and lower sets, respectively, said link members J being pivotally secured to the plates by means of pivot pins *j*. Having swiveled connection with the upper link member J, intermediate its ends and depending therefrom, is a forked member *j*'. The stanchion A is suspended from said upper link member J by means of a flexible member or stanchion chain L, the upper end of which is attached between the arms of said forked member *j*' by a bolt *j*² passing through the same. The lower end of said stanchion chain L is connected to the upper end of the stanchion A by a bolt *j*³ passing through its lower end and through the upper end of the forked member *b*⁶ between the arms of which the lower end of said chain is located. The lower end of the stanchion A is attached to the lower link member J by a lower stanchion chain L'. Said lower chain L' has its upper end connected with the lower end of the stanchion by a pivot bolt *b*² passing through its upper end, and its lower end

connected to an upright forked member *j*' having swiveled connection with the lower link member J. The stanchion A is supported in a vertical or upright position in the stall, preferably at the inner or manger end thereof, by means of the devices above described, which are adapted to permit horizontal adjustment of the stanchion, in the manner set forth in my hereinbefore mentioned prior application, and as shown in dotted lines in Fig. 3, and in full lines in Fig. 4. By reason of the adjustment of the stanchion to either side of its central or intermediate position, a long or a short animal may be held in the stall in proper position with respect to the gutter at the open end or entrance thereof. Moreover, in the case of a cow, the stanchion may be adjusted so as to hold the same in proper place in the stall with respect to the milker sitting at the entrance or open end thereof.

The subject-matter of my present invention embraces features as follows: Referring to the drawings, and especially to Fig. 5 thereof, the casting *b*, as hereinbefore stated, is rigidly secured to the lower end of the side member or bar B of the stanchion and constitutes one of the members of the hinge for connecting the lower end of said bar B with the corresponding end of the bar C. Said casting *b* is provided, above the eye therein, with an integral stop-member or lug *b*⁸. Said lug *b*⁸ projects laterally from the said casting *b* and the lower inclined part of the bar B to which said casting *b* is attached. Said lug *b*⁸ projects to such a distance from the pivot bolt *b*², that when the side members or bars B, C are being closed, that is, when the upper end of the bar C is being moved toward the bar B in closing the stanchion, the stop-member or lug *b*⁸ will come into contact with the adjacent or inner edge of the part or stop-member *c*³ integral with the casting *c*, rigidly secured to the lower end of the bar C, and stop movement of the bar C, before the upper ends of said bars B, C come together. To bring the upper end of the bar C into contact with the corresponding end of the bar B, it is necessary to force the bar C inward from the position it occupies when stopped by the stop-members *b*⁸ and *c*³, with the result, that that portion of said bar C above the stop-member *c*³ is sprung or flexed and is maintained under tension when held in locked position. By reason of the construction above described, when the upper ends of the bars B, C are locked together, the elasticity of the bars themselves will tend to spring them apart. It follows, therefore, that as soon as the finger piece *b*⁷ of the latch at the upper ends of the bars B, C is depressed, to unlock the bars, said bars will immediately and automatically spring apart, thus avoiding the necessity of grasping the bars to

swing them apart in order to open the stanchion. This "self-opening" feature of the stanchion is of considerable advantage, not only when considering one stanchion, 5 but especially when considering a number of stanchions, one in each stall, that are arranged side by side. A man passing in front of the cattle in the stalls need only depress the finger piece of the latch of each stanchion 10 as he walks along, and side bars B, C of each stanchion will immediately swing open.

It is obvious from the above, that the stanchions thus made are more readily and quickly opened than in the case of stanchions so made that two hands are required 15 to open them, as heretofore.

Instead of the coacting parts or stop-members b^s and c^s being integral with the castings constituting the members of the 20 hinge for the lower ends of the bars B, C, as shown, it is to be understood that each of the bars B, C may be provided with either integral or attached stop-members so arranged as to come into contact with each 25 other before the upper ends of the bars are brought together in closing the stanchions. It is essential, however, that said stop-members be arranged to contact with each other at a point above, but adjacent to, the point 30 of pivotal connection of the side bars of the stanchion, in order to obtain the effect of flexure of the side bars in closing them, and their automatic opening when unlatched, as hereinbefore stated.

35 While I have shown and described herein certain mechanical details of construction and arrangement of the several parts of the preferred form of my device illustrated, it is to be understood that these may be 40 changed and variously modified without departing from the spirit of my invention and I do not wish to be limited to the construction and arrangement shown herein, except as pointed out in the appended claims.

45 What I claim is—

1. A cattle-stanchion, comprising two side members or bars, means providing connection for said bars at one end of the stanchion, permitting swinging movement of 50 said bars with respect to each other and including a stop member; one of said bars being resilient and provided with a stop member adapted to come into contact with the first-mentioned stop-member, before the 55 stanchion is closed, so that the resilient bar will be under tension and will tend to spring outwardly when the stanchion is closed.

2. A cattle-stanchion, comprising two side members or bars having pivotal connection 60 at one end of the stanchion and detachable connection at the other end of the same, each bar being provided intermediate its end with a stop-member, and that part of each

bar between its swinging end and its stop-member being resilient, said stop-members 65 being adapted to come into contact with each other, before the swinging ends of said bars are brought together in closing the stanchion, so that the resilient portions of said bars will, when the stanchion is closed, 70 be under tension.

3. A cattle-stanchion, comprising two resilient side members or bars having pivotal connection at their lower ends and detachable connection at their upper ends, said 75 bars being provided adjacent their lower ends and above their point of pivotal connection, with stop-members adapted to come into contact with each other, before the upper ends of said bars are brought together in closing the stanchion, so that said bars will, when the stanchion is closed, 80 be under tension.

4. A cattle-stanchion, comprising two resilient side members or bars having their 85 upper and lower ends directed inwardly toward each other, means providing pivotal connection for said bars at their lower ends, and means providing detachable connection for said bars at their upper ends; one of 90 said bars being provided, at its lower end, above its pivotal connection with the other bar, with a lug adapted to come into contact with the lower end of said other bar before the upper ends of said bars are 95 brought together in closing the stanchion, so that said bars will be under tension when the stanchion is closed.

5. A cattle-stanchion, comprising two resilient side bars having their upper and 100 lower ends directed inwardly toward each other, means providing detachable connection for said bars at their upper ends, a yoked member secured to the lower end of one of said bars, an eyed member secured to 105 the lower end of the other of the said bars and adapted to enter between the arms of said yoke, and a pivot bolt connecting said yoke and eyed members together; one of said members being provided, above the 110 point where said pivot bolt passes through the same, with a lug adapted to come into contact with the other member before the upper ends of said bars are brought together in closing the stanchion, so that said 115 bars will, when the stanchion is closed, be under tension and tend to spring apart.

In testimony, that I claim the foregoing as my invention I affix my signature in the presence of two witnesses, this 18th day of 120 December, A. D. 1912.

WILLIAM F. JACOBS.
